UNITED STATES PATENT OFFICE.

HARRY E. CRIFE, OF CHICAGO, ILLINOIS, ASSIGNOR TO UNDERWOOD TYPEWRITER COMPANY, OF NEW YORK, N. Y., A CORPORATION OF DELAWARE.

TYPEWRITING MACHINE.

Application filed July 2, 1925. Serial No. 41,016.

This invention relates to a novel typewriting machine, which is readily convertible to use either for continuous billing work or for ledger-posting, little transformation 5 being required to render the machine capable of handling either class of work.

According to this invention, there is provided web-handling equipment including a displaceable platen-frame, a delivery table 10 and a knife for severing the typed form-sections of the web. This mechanism may be of the character disclosed in the patent to William F. Helmond, No. 1,572,139, granted February 9, 1926.

15 For ledger-posting the delivery table is equipped with a pair of oppositely-disposed side-edge gages which position or locate the ledger-sheet for typing the desired entries thereon. The delivery table thus forms a 20 sheet-gaging table.

The web-severing knife is positioned between the sheet-gaging table and the printing line of the platen, the knife being so constructed that it is manipulatively detachable from the machine, so as not to interfere with the gaging operation incident to the introduction of a ledger-sheet for typing.

When it is desired to transform the machine for ledger-posting, the web may be 30 folded back at the rear of the machine.

Other features and advantages will hereinafter appear.

In the accompanying drawings,

Figure 1 is a front view, in elevation, of 35 an Underwood fan-fold combined typewriting and computing machine.

Figure 2 is a cross-sectional view, in elevation, through the line 2-2 of Figure 1, and shows the machine as applied to fan-fold billing-work.

Figure 3 is a diagrammatic cross-sectional view, in elevation, through the center of the machine, showing the machine as applied to ledger-posting work.

45 Figure 4 is a perspective view, showing the removable feature of the fan-fold knife.

This invention is illustrated as applied to a combined typewriting and computing machine of the fan-fold or continuous billing type. The typewriting mechanism comprises a platen 10, around which a work-sheet is fed, by means of co-operating feed-rolls 11, to the printing point in front of the platen to be typed upon by means of 50 type-bars 12. The computing mechanism

comprises a series of computing registers, not shown, controlled by the numeral-keys of the typewriter. Each register is effective in certain computing zones of the carriage, the carriage being positioned by means of 60 tabulating keys corresponding to the computing zones. The computing mechanism is of the nature illustrated in the patent to Becker, No. 1,296,354, dated March 4, 1919, and is generally indicated in the drawings 65 by the numeral 13.

A web 14, having a plurality of fan-folded plies, upon each of which plies bill-forms are printed, each form registering with other forms printed in the underlying plies of the 70 web, is interleaved with carbons and is passed over a cross-bar 15, between side gages 16. The web is then inserted in the machine, leading edge first, down a paper-table 17 under and around the platen co-operating with the feed-rolls 11 to be fed 75 therearound past the printing point in front of the platen behind a knife 18 and up over a front table 19 to be gaged in form-lengths against a gage 20 slidably mounted upon a 80 bar 21 and settable thereon by means of a screw 22.

In order to strip the carbons and to present them to a fresh portion of the web, it is necessary to straighten out the web, 85 and, to this end, there is provided mechanism comprising a swingable platen-frame having side plates 23 pivotally mounted at 24. The platen is connected to the line-spacing mechanism (not shown) and to finger-pieces 90 25 mounted on shafts 26 in line with the platen-axle 27, by means of gears 28 and 29, the latter fast to the platen-axle. The two gears mesh with idle pinions 30 on the side plate 23. Said side plates are connected 95 by a cross-piece 31, against which the table 19 and the bar 21 are secured, respectively at the front and at the rear thereof.

Upon displacing the carbons from the typed forms, the platen is again lowered to 100 its normal position and the platen-frame is locked in position by means of a latch 32 engaging with a pin 33 fast to one of the side plates 23, whereupon the typed forms are torn off against the knife 18.

105 When it is desired to transform the machine for ledger-posting, the web 14 is withdrawn from the machine and is folded upon the carbon-carrier. The knife 18 is also taken off the machine preparatory to inserting 110

a ledger-sheet 14^a around the platen. The ledger-sheet is passed between the gages 16 and is inserted leading edge first down the rear table 17 around the platen and up in front thereof, in which position it is held, bearing upon the platen, by means of front wire fingers 34.

In order to render the knife manipulatively detachable from the machine, there is provided a bayonet-slot 41, at one end, engaging with a stud 40, the other end being provided with an open slot 42 and a binding screw 39. Referring to Figure 4, in which the knife 18 is shown in connection with two operating cam-plates 35, it will be noted that the cam-plates are provided with tabs 36, each having a tapped hole 37 therein for receiving the threaded portions 38 of the stud 40 and the screw 39. In order to position the knife the slot 41 is first engaged with the stud 40, and then the knife is pulled to one side to engage the open slot with the screw 39, thus forcing the screw 40 into an enlarged portion 43 of the opening 41, thereby locking the knife in a fixed position, in which position it is held by tightening the screw 39.

To facilitate the aligning of the ledger-sheet, front gages 44 are provided. These gages form with the front table 19 a sheet-gaging table for locating the ledger-sheet. The gages are adjustably secured to the

front table 19 by means of screws 45 through slots 46.

In the Underwood fan-fold billing machine the knife 18 is swingable to a position below its normal cutting-off position, to serve as a means to guide the leading edge of the web. The knife is rockably mounted on the platen-axle 27 and is actuated by a finger-piece 47 having a pin 48, fast thereto, designed to engage cam-slots 49 in the cam-plates 35. This same feature is retained in the present invention, no changes being made to the knife-operating mechanism.

Variations may be resorted to within the scope of the invention, and portions of the improvements may be used without others.

Having thus described my invention, I claim:

A typewriting machine for selectively typing either upon a work-web or a work-sheet, including, in combination, a platen, a platen-displacing frame, the latter having side plates and a delivery table extending between the plates, a pair of oppositely-disposed side-edge gages carried by said table for gaging the work-sheet, a leading-edge gage for the work-web, and a web-severing knife disposed between the side-edge gages and the printing line of the platen, said knife being manipulatively detachable from the machine.

HARRY E. CRIPE.
